United States Patent Office

Des. 223,045
Patented Feb. 29, 1972

223,045

THREE-WHEELED POWERED VEHICLE

William S. Stull, Los Angeles County, Calif.
(15214 Midcrest Drive, Whittier, Calif. 90604)

Filed Sept. 16, 1970, Ser. No. 25,020

Term of patent 14 years

Int. Cl. D12—13

U.S. Cl. D90—8

FIG. 1

FIG. 2

FIG. 3

FIG. 4

FIG. 1 is a perspective of a vehicle looking toward the rear thereof having the ornamental design of the present invention.

FIG. 2 is a frontal view of the vehicle of FIG. 1.

FIG. 3 is a perspective of the vehicle of FIG. 1, looking towards the front of the vehicle.

FIG. 4 is a rear view of the vehicle of FIG. 1.

FIG. 5 is a perspective view of a modified form thereof. I claim:

The ornamental design for a three-wheeled powered vehicle, as shown and described.
